BOBBY PIN OPENER RING OR THE LIKE

George W. Deuillet, Massapequa, N. Y.

Application December 3, 1947, Serial No. 789,367

6 Claims. (Cl. 132—1)

1

This invention is concerned with a hair pin opening device. More particularly it concerns a hair pin or bobby pin opening device which may be positioned on finger or wrist of one hand and permitting the use of the other hand to manipulate the pin in conjunction with the device to spread the arms thereof.

An object of this invention is to provide a device of the character described which comprises a mounting adapted to be positioned on a support such as the finger, wrist, or the like, a wall on said mounting and recessed means on said wall including an upstanding back wall and a top wall extending from the upper end of said back wall, whereby the end of the longer arm of a bobby pin may abut said back wall and is held down by said top wall while the end of the shorter arm of the pin is lifted away from the longer arm of the pin by the operator.

Another object of this invention is to provide in a device of the character described which comprises a split loop mounting which may be positioned on a finger, said mounting comprising a flat wall and an upstanding wall pressed out of said flat wall, a top wall extending from the upper end of said back wall and end walls interconnecting said flat wall, back wall and top wall, said flat wall being adapted to guide the longer arm of a bobby pin as it is pushed into abutment with said back wall and said end walls are adapted to retain the end of said pin arm beneath the top wall and to prevent the same from sliding sideways out of engagement with said back wall.

Still another object of this invention is to provide in a device of the character described, a split loop mounting comprising a flat wall disposed opposite the split in the loop, said wall being formed on a central portion thereof with a hollow member pressed out of the plane of said wall, said member comprising an upstanding back wall, a top wall extending from the upper end of said back wall and end walls, thus forming a slot or bight at its front portion, whereby a bobby pin may be positioned with a portion of its longer arm disposed in contact with said flat wall and the end portion thereof projecting into said slot or bight, the end of said arm abutting the back wall and held down by said top wall while the shorter arm of said bobby pin is lifted by the thumb and end finger of the operator away from said longer arm.

Yet a further object of this invention is to provide a unitary device of the character described which is inexpensive to manufacture,

2

which shall be attractive in appearance, easy to manipulate and yet practical and efficient to a high degree in use.

Other objects of this invention will in part be obvious and in part hereinafter pointed out.

The invention accordingly consists in the features of construction, combinations of elements, and arrangement of parts which will exemplified in the construction hereinafter described, and of which the scope of application will be indicated in the following claims.

In the accompanying drawing, in which is shown various possible illustrative embodiments of this invention;

Fig. 1 is a perspective view of a bobby pin opening device embodying the invention, and shown positioned on the finger of the user thereof;

Fig. 2 is a side elevational view of the device embodying the invention;

Fig. 3 is a sectional view taken on the line 3—3 of Fig. 2, with a bobby pin positioned thereon and

Fig. 4 is a top plan view thereof.

Referring now in detail to the drawing, 10 designates the hair pin spreading device embodying the invention. The same comprises a mounting in the form of a ring like band or loop member 11, preferably split as at 12. The curved arms or spring fingers 13 of the member 11 which terminate short of each other are interconnected by a horizontal, substantially rectangular portion 14 disposed opposite the split or space 12 in the loop which separates the ends of said fingers. The portion 14 comprises a raised, flat wall or floor portion 15 and a marginal, outwardly inclined rim 16 extending downwardly therefrom.

The wall 15 comprises parallel side edges 17 and parallel end edges 18. A central transverse upwardly recessed riser or catch portion of member 19 radially offset and adapted to receive the longer arm of a hair pin, extends upwardly from the wall 15 of the portion 14. The member 19 which may be pressed from the wall 15, thus forming an opening or recess 19a in the wall 15, comprises an inclined upwardly extending back wall or part 20 parallel to edges 17 and extending between edges 18. A curved top wall or part 21 extends from the upper end of wall 20 and end walls or parts 22 interconnect the walls 20, 21 with the wall 15. The forward edge of the top wall 21 is spaced from the wall 15. A longitudinal slot 23 is formed in the front end opposite the back wall 20 and said slot communicates with recess 19a and is disposed between the end parts

or walls 22. The member or portion 19 may be disposed intermediate the edges 17 of wall 15. It will be apparent that the slot or bight in member 19 is disposed in a plane which is transverse to the plane of the wall 15.

In using the device 10, it may be slipped on the finger of the operator as shown in Fig. 1, the split 12 in the loop allowing for comfortable fit. The device is positioned on the finger with the slot or bight 23 in the member 19 facing forwardly. The 10 bobby pin 25 which is to be opened, is positioned with the undersurface of its longer arm 26 moving along the wall 15 and its end portion 27 projecting into slot 23. The end of the arm 26 abuts the back wall 28 of the member 19. The rear or 15 looped portion 28 of the bobby pin may be supported by the thumb and middle finger of one hand, at the same time urging the end 27 of the pin into abutting engagement with the back wall 20 of the abutment member 19. This leaves the 20 forefinger free to lift up the end 29 of the shorter arm 30 of the bobby pin by means of the nail on the forefinger, as shown in Fig. 3.

It will be apparent that the curved upper wall 21 of the member 19 will retain the end 27 of the longer arm 26 of the bobby pin against upward movement, while the end 29 of the shorter arm 30 is being lifted. Also, the end walls 22 keep the end 27 of the arm 26 from sliding sideways out of engagement with walls 20, 21.

The depth of the chamber or bight 23 is less than the difference in the lengths of the arms 26, 30, of the bobby pin. This provides a space between the end 29 of the arm 30, and the forward edge of the top wall 21 of the member 19, when the device is in use and permits access to the end 29 of the arm 30 for lifting purposes.

The length of the slot 23 permits easy introduction of the end 27 of the arm 26 of the bobby pin, particularly when the user is in a hurry.

It is understood that the member 11 may be of such dimensions and shape as to permit mounting the device on the wrist, arm or any other suitable support.

The rim 16 is adapted to raise the flat wall 15 above the finger or other support on which the device is mounted.

The member 19 may be readily formed by drawing the wall upwardly by means of suitable dies, or the like, to form the back wall 20, top wall 21, and end walls 22 in a single operation. Also, the entire device may be made in a single operation by die casting or molding procedures. If desired, the member 19 may be made up separately and then secured to the flat wall 15 of the mounting 11 by soldering, etc.

It will thus be seen that there is provided a device in which the several objects of this invention are achieved, and which is well adapted to meet the conditions of practical use.

As various possible embodiments might be made of the above invention, and as various changes might be made in the embodiment above set forth, it is to be understood that all matter herein set forth or shown in the accompanying drawing is to be interpreted as illustrative and not in a limiting sense.

Having thus described my invention, I claim as new and desire to secure by Letters Patent:

1. A hair pin opening device comprising a flat wall and a downwardly and outwardly inclined marginal portion surrounding said wall at the front, rear, and sides thereof, a pair of curved spring fingers extending from the side marginal portions and terminating short of each other to

provide a spring clip to engage the finger of a user, a central transverse upwardly recessed portion extending from said wall, said recessed portion having a rear part and a top part, and the front of said upwardly recessed portion being formed with a longitudinal slot extending down to the upper surface of said wall, said slot terminating at the underside of said wall.

2. A hair pin opening device comprising a flat wall and a downwardly and outwardly inclined marginal portion surrounding said wall at the front, rear, and sides thereof, a pair of curved spring fingers extending from the side marginal portions and terminating short of each other to provide a spring clip to engage the finger of a user, a central transverse upwardly recessed portion extending from said wall, said recessed portion having a rear part and a top part, and the front of said upwardly recessed portion being formed with a longitudinal slot extending down to the upper surface of said wall, said slot terminating at the underside of said wall, the ends of said top part of said upwardly recessed portion being connected to said wall by end parts located at the ends of said slot.

3. A hair pin opening device comprising a flat wall and a downwardly and outwardly inclined marginal portion surrounding said wall at the front, rear, and sides thereof, a pair of curved spring fingers extending from the side marginal portions and terminating short of each other to provide a spring clip to engage the finger of a user, a central transverse upwardly recessed portion extending from said wall, said recessed portion having a rear part and a top part, and the front of said upwardly recessed portion being formed with a longitudinal slot extending down to the upper surface of said wall, said slot terminating at the underside of said wall, the ends of said top part of said upwardly recessed portion being connected to said wall by end parts located at the ends of said slot.

4. A hair pin opening device comprising a flat wall, a pair of curved spring fingers extending from the sides of said wall and terminating short of each other to provide a spring clip to engage the finger of a user, a central transverse upwardly recessed portion extending from said wall, said recessed portion having a rear part and a top part, and the front of said upwardly recessed portion being formed with a longitudinal slot extending down to the upper surface of said wall, said slot terminating at the underside of said wall, the ends of said top part of said upwardly recessed portion being connected to said wall by end portions located at the ends of said slot.

5. A hair pin spreading device comprising a ring-like band adapted for positioning on the finger, a portion of said band being radially offset and forming substantially a floor portion, a riser formed above said floor portion, said riser formation having a rear wall and a slot opening opposite said wall, said slot opening to receive a prong of a hair pin and said wall limiting the length of insertion of said inserted prong in said slot opening, whereby the extremity of said inserted prong may be prevented from moving while the other prong of said hair pin is manually spread away therefrom.

6. A hair pin spreading device, comprising a ring-like band adapted for positioning on the finger, a portion of said band being radially offset and forming a floor, a catch formation formed

above said flooring, and a stop integral with said catch formation for limiting the insertion of one of the prongs of a hair pin in the said catch formation whereby the extremity of one prong may be prevented from moving while the other prong of the hair pin is manually spread away therefrom, said floor formation preventing said wearer's finger from contacting with the inserted prong aforesaid.
